UNITED STATES PATENT OFFICE.

LAWRENCE B. GRAY, OF BOSTON, MASSACHUSETTS, ASSIGNOR TO HYDRAULIC VACUUM DREDGING COMPANY, OF WILMINGTON, DELAWARE, A CORPORATION OF DELAWARE.

APPARATUS FOR COLLECTING PRECIOUS METALS.

1,056,662.

Specification of Letters Patent.

Patented Mar. 18, 1913.

Application filed August 29, 1910. Serial No. 579,409.

To all whom it may concern:

Be it known that I, LAWRENCE B. GRAY, of Boston, in the county of Suffolk and State of Massachusetts, have invented certain new 5 and useful Improvements in Apparatus for Collecting Precious Metals, of which the following is a specification.

This invention relates to an apparatus adapted to be used in placer mining for collecting the precious metals when the same are separated by washing from the deposits of sediment in which they are contained.

The particular object of the present invention is to collect those particles of the 15 metals which are too fine to sink into the water carrying them, and which are known as float gold, float silver, etc., as the case may be.

Accordingly the apparatus consists of a 20 sluice or flume through which a stream of water carrying the deposits with which the particles of precious metals are mingled, is led, with a device of such character as to be able to retain the particles of metal, and located in such a position as to intercept 25 those particles which float upon the surface of the stream. Also, the apparatus includes, in combination with said device, a set of movable baffles operated by the stream to 30 bank up the water adjacent to the device, while permitting solid matter carried by the stream to pass, which is also a motor for so moving the device as to present different parts of its surface to the floating metal, and 35 to carry such surface past and in contact with a scraper which removes the material adhering to such surface.

In the accompanying drawings I have 40 illustrated an apparatus embodying the principles of my invention, and being one of many forms in which these principles may be embodied.

Figure 1 represents the apparatus in side elevation. Fig. 2 represents a longitudinal 45 section of the same. Fig. 3 is a plan view, and Fig. 4 is a cross section.

The same reference characters indicate the same parts in all the figures.

At the outset I desire to state that this 50 apparatus is adapted to be used for collecting the fine particles of any of the precious

metals which occur in nature in a state permitting them to be separated from the deposits with which they are mingled, by washing. As gold is the metal which most 55 commonly occurs in this state, however, and as it is my purpose to use this apparatus mainly in the mining of gold, I shall refer in the following specification to the metal acted upon as gold, for the purpose merely 60 of convenience of description, and to avoid the use of too many words, without, however, intending to limit myself in any manner to the kind of metals which I propose to save by the use of the apparatus. 65

Referring to the drawings, *a* represents a flume or sluice through which the water charged with the gravel and dirt containing gold is caused to flow. At a suitable point in the sluice is located a drum *b* which is 70 carried by trunnions *c* having bearings in boxes *d* in the sides of the sluice. The drum is so mounted that its lower part dips into the water in the sluice, and is preferably adjustable so that it may be thus partly submerged when the water is at any height, and may also be submerged to a greater or less extent as desired. For this purpose the boxes *d* are adjustably contained in vertical guides *e*, and are provided with adjusting 75 screws *f* passing through yokes *g* and carrying nuts *h*. The yokes cross the guideways and the nuts bear on the yokes, thereby enabling the boxes and with them the drum to be adjusted up or down. In the bottom of 80 the sluice, directly below the drum *b* is a shallow pocket *i* containing a quantity of mercury. The drum is preferably made of copper, with its outer surface silver plated, and covered with mercury. The mercury is 85 necessary to form an amalgam with and pick up the gold floating on the stream, and the plating of silver on the drum is necessary to make the mercury stick and spread over its surface, while copper is used as the 90 material for making the drum, because it is best adapted to retain a plating of silver. Above the drum is a trough or tank *j* containing mercury, and having outlets *j'* in its bottom through which small quantities of 95 the mercury are continually fed upon the drum. At the rear side of the drum is a 100

scraper *k* which bears against the surface of the drum, and when the latter is rotated, scrapes off the amalgam upon its surface. The scraper also is above the mercury in the pocket *i* and the amalgam which falls from it drops into the mercury and is kept by the latter from being carried on with the water and gravel. This descending current of amalgam falls through the stream of pulp passing between the drum and pocket and catches any particles of metal which may escape the drum. The scraper may be a brush or brushes, and is conveniently a strip of wood, leather or the like, held at one edge in and projecting edgewise from a bar *l*, the latter being pressed yieldingly toward the drum by springs *l'* and supported by studs *l''* passing through a stationary bar *m* spanning the flume. In the embodiment of the invention here shown, the bar *m* is fastened to plates *n* and *n'* which are slotted so as to slip over the boxes *d*, and are contained between the sides of the flume and the ends of the drum. The mercury supply trough *j* is also secured at its ends to these plates. The plates are further connected together by a cross-bar *o*, which also provides a guard for the drum, protecting the same from injury. These details of construction, however, are merely optional and may be varied and modified without departing from the spirit of the invention. On the pins *l''* previously referred to are threaded adjusting nuts *p* which secure the scraper.

Secured to the boxes *d* in which the drum trunnions are held are plates shown in section in Fig. 4, and designated by the letter *n²*, which cover the openings in the walls of the sluice wherein are the vertical guides *e* for the boxes. The plates *n²* are arranged both on the inside and outside of each wall of the sluice and cover the spaces between the guides so that water will not leak out even when the boxes are raised above the bottoms of such spaces as shown in Fig. 4. The plates *n*—*n'* above described have slots which enable them to fit over the inner cover plates *n²*.

A convenient motive mechanism for rotating the drum is found in the water wheels *q* and *q'*, the shafts *r* and *r'* of which are supported in bearings on the opposite walls of the flume. These water wheels are caused to rotate in unison by means of gears *s* and *s'* on their shafts respectively meshing with an intermediate idler wheel *s²*. On the shaft of one of the wheels is a sprocket *t* which drives, by means of a chain *t'*, a sprocket *t²* on the shaft of the drum. Any suitable form of water wheel may be used differing if need be from that here shown, which consists merely of vanes secured to armed spiders on the shafts *r* and *r'*. By reason of the water wheels the drum is kept in rotation in such a direction that the por-

tion which dips into the water travels in the same direction as the stream. Preferably the wheels are so arranged that one of the blades of one dips squarely into the stream while the blades of the other are inclined to the flow of the stream. In other words, whenever a blade of one of the wheels projects vertically downward from its axis the two lowermost blades of the other wheel are inclined and make equal angles with a vertical line passing through the axis of that wheel. There is a coaction between the paddle wheels and the amalgamating drum in the recovery of precious metal and irrespective of the function which said paddle wheels have of rotating the drum. This is that the blades of the paddle wheels act as revolving and movable baffles or dams which obstruct the flow of water through the sluice, causing the water to back up around the drum to a height greater than that due to the depth at which the drum is set in the sluice, and periodically withdraw to allow the gravel and stones carried in the stream, to pass on down the sluice. To explain further, it is to be understood that the stream which passes through the sluice carries gravel and stones, some of the latter of considerable size. It is objectionable to set the drum so near the bottom of the sluice that there will be any danger of its being struck by these stones, as the stones would dent the drum, preventing an even coating of the quicksilver and removal from the drum of amalgam. Neither is it feasible in many instances to direct a large volume of water through the sluice in proportion to the amount of gravel and stones so as to submerge the latter to any great depth, because in many mining regions the supply of water is limited and must not be wasted. Hence it is usually impossible to set the drum so that it dips much below the surface of the freely flowing stream without liability of the drum being struck by stones. On the other hand the efficiency of the apparatus in collecting float metals is greatly increased by having as great an extent as possible of the surface of the drum in contact with the water. Hence the value of the revolving baffles or paddles *q*, *q'*. When any one of these paddles extends downwardly into the stream, it largely impedes the flow thereof, causing the level to rise locally in the vicinity of the drum, increasing the extent of the submerged surface of the drum, without any increase in the actual quantity of water flowing, and without incurring danger of stones striking the drum. It is further necessary that the blades should be spaced angularly wide apart, in order to avoid danger of the stones wedging between the blades, hence they are set at an obtuse angle with each other as shown. Finally it is necessary that the backed up condition of the water should be practically continuous, 130

while at the same time provision be made to prevent the accumulation of stone and gravel, hence the provision of the two wheels or sets of baffles; so arranged that when the 5 baffles of one set are so placed as not to obstruct the stream, a baffle of the other set does obstruct the stream. The two sets of baffles in combination constitute a sort of lock which permits the solid matter to pass. 10 while maintaining high level of water at the drum. The gearing between the two sets of baffles maintains this relation between them.

In placer mining a considerable portion of 15 the gold which is found consists of such fine particles as to float on the water, and is therefore known as float gold. Many schemes have been proposed and tested for collecting this float gold, but no plan hitherto tried has been wholly successful. My 20 invention solves this problem in that it furnishes an amalgamating surface directly in the path of the float gold to pick up the same, and causes a fresh surface to be constantly presented to the advancing gold, so that it will be in condition to pick up the gold as fast as it is carried down by the flowing stream. This effect is produced by virtue of the rotary movement of the drum 25 in the manner above described. The apparatus is thus very simple and as it is driven by the power of the stream itself, it is economical as well. Such of the precious metal as sinks during the progress of the stream 30 through the sluice and falls into the pocket is retained by the quicksilver therein, and any of the metal which escapes contact with the mercury on the drum and that in the pocket, is caught by the amalgam passing 35 through the stream from the drum to the pocket, and saved. Thus a descending curtain of amalgam is provided which supplements the action of the mercury on the drum and the mercury or amalgam in the pocket 40 in retaining the precious metals.

45 I claim:

1. An amalgamating apparatus comprising an open sluice or flume, a drum having a smooth amalgamating surface supported 50 between the walls of the sluice above the bottom of the sluice, so as to collect the fine float metal and permit the gravel to pass freely beneath it, a mercury pocket below and spaced from the drum, means for rotating the drum, a scraper extending the 55 length of the drum and bearing on its surface at a point over said pocket, and adapted to discharge the amalgam directly into the pocket and through the stream of pulp 60 passing between the drum and pocket.

2. An amalgamating apparatus comprising an open sluice or flume, a drum having a smooth amalgamating surface supported 65 between the walls of the sluice at a height above the bottom of the sluice whereby to

collect fine floating particles of metal borne by the stream passing through the sluice, means for continuously feeding mercury to the top of the drum along its entire length, and a scraper bearing on the drum along its entire length, for continuously removing amalgam therefrom and producing a descending current of amalgam, through which the stream flows and by which particles of metal escaping the drum are 70 caught. 75

3. In an amalgamating apparatus the combination with a sluice of an amalgamating drum set therein and means for maintaining a relatively high level of water at the locality of said drum while permitting the drum to remain sufficiently high above the bottom of the sluice to permit stones to pass without striking it, said means comprising a pair of baffles located at the downstream side of the drum whereby to obstruct the flow of water, said baffles being operated by the current so as alternately to be withdrawn from and projected into the drum, whereby to allow solid substances to pass 80 them. 85

4. In an amalgamating apparatus the combination with a sluice, an amalgamating drum set into said sluice, a plurality of sets of revolving baffles located at the downstream side of the drum, each of said sets of baffles comprising a shaft and blades secured radially to said shaft and making obtuse angles with one another, said shafts being geared together to rotate in unison, and being driven by impingement of the stream 90 against the blades, the blades on the shafts being so arranged that when a blade of either dips into the stream, the blades of the other are withdrawn therefrom. 100

5. In an amalgamating apparatus the combination with an open sluice or flume, a drum having journals rotatably held in the side walls of the sluice, and having an amalgamating surface, a mercury reservoir, and means for removably supporting said reservoir in close proximity to the upper side of the drum, comprising plates formed to enter respectively between the ends of the drum and the sides of the sluice, and having 110 slots to pass over the journals of the drum, the reservoir extending between said plates and being secured at its ends thereto. 115

6. In an amalgamating apparatus, the combination with an open sluice or flume, a drum having journals, boxes in which said journals are contained mounted in the side walls of the sluice, plates contained between the ends of the drum and the side walls of the sluice, having slots to pass over and embrace the boxes, whereby the plates are supported and held in place, a mercury reservoir secured at its opposite ends to the plates and extending from one to the other over the top of the drum, arranged to feed mer- 125 130

cury upon the drum, a bar at one side of the drum secured at its ends to the plates, a scraper supported by said bar and movable toward and from the drum, and springs 5 acting between the bar and scraper to press the latter against the drum; the plates, reservoir and scraper being removable together from the drum, and being held in

such relation to one another when so removed as to permit ready replacement.

In testimony whereof I have affixed my signature, in presence of two witnesses.
